UNITED STATES PATENT OFFICE.

ALBERT H. JOHNSON, OF WASHINGTON, DISTRICT OF COLUMBIA, ASSIGNOR TO
NATIONAL ELECTRICAL SUPPLY COMPANY, OF WASHINGTON, DISTRICT OF
COLUMBIA, A CORPORATION OF VIRGINIA.

ELECTRICAL-RESISTANCE WIRE.

1,344,406.

Specification of Letters Patent. Patented June 22, 1920.

Application filed December 19, 1919. Serial No. 345,972.

To all whom it may concern:

Be it known that I, ALBERT H. JOHNSON, a citizen of the United States, residing at Washington, in the District of Columbia, 5 have invented certain new and useful Improvements in Electrical-Resistance Wire, of which the following is a specification.

This invention relates to electrical resistance elements, and it comprises a resistance element made of substantially circular wire, 10 said wire being bent or crimped to form loops and intermediate, connecting sections between said loops, the connecting sections being flattened on opposite sides, and said 15 flattened surfaces being corrugated or roughened; all as more fully hereinafter set forth and as claimed.

In the manufacture of electric heating appliances wire having a high degree of resistance is employed. This wire is generally bent or crimped to form loops and connecting sections between the loops, producing substantially U-shaped portions, with inverted 20 U-shaped portions therebetween, the legs 25 of the U-shaped portions being connected to the adjacent inverted U-shaped portions. The units are generally arranged in a substantially circular form by bending the unit 30 near the center to produce substantially parallel sections, and then forming the unit into a spiral, with the bent portion at the center of the spiral, and the two ends at the periphery thereof. When a plurality of these 35 coils are employed, they are arranged on top of each other with a strip or sheet of mica, or other insulating material, separating them.

When wire of substantially circular cross 40 section is crimped in this manner, and is then bent in any particular manner to give it a certain external shape, there is a strong possibility of the individual loops coming in contact with each other on the inside of the 45 bend. In electrical resistance elements and especially where the loops are arranged in a flat spiral, this tendency is noted and it is necessary to avoid it. If two sections of the wire touch each other, one of the loops is 50 short circuited and the current does not pass through it. The result is that the amount of heat that the loop is estimated to furnish is not obtained.

I have found that where the sides of a

loop are first flattened to produce elongated 55 sections, that this difficulty of short circuiting is avoided and that the rounded ends of the loops are kept spaced from each other.

Another important advantage of my invention is obtained where a number of heating elements are employed, arranged one above the other and separated from each other by thin strips of mica or other insulating material. With a unit of wire in 60 which the cross section of the individual loops is substantially circular, there is a tendency of the mica plates to move relative to the units and thus permit the units to 65 come in contact with each other. If the insulation on the wiring becomes worn at any point, short circuiting occurs from one unit 70 to the other.

Where the sides of the loops are flattened 75 to produce elongated sections, this tendency of the insulating strip to work out of position is greatly diminished. Furthermore, I have found that roughening the sides forming the elongated sections, practically 80 eliminates the tendency of the insulating strips to move. When a heating element consisting of several units is assembled, a slight amount of pressure may be applied as 85 each strip of mica or other insulating material is being put in place, causing the roughened portions of the resistance element to embed a slight distance in the mica and thus 90 eliminate any tendency to relative movement.

In the accompanying drawings, I have shown one embodiment of this invention.

In this showing,

Figure 1 is a plan view of an electrical resistance element wherein the sides of the 95 individual loops have been flattened.

Fig. 2 is a sectional view on the line 2—2 of Fig. 1.

Fig. 3 is a sectional view on the line 3—3 of Fig. 1, and

Fig. 4 is a plan view of a resistance element formed of flattened and roughened resistance wire.

Referring to the drawings, the reference numeral 1 designates a strip of wire that has 105 been bent back and forth to produce loops 2. These loops are connected by intermediate sections 3 and these sections have been flat-

tened on the two outer sides, as shown at 4 and 5. The sections 3 may be flattened by passing the wire between two rolls and applying pressure thereto, or by any other desired method. After the sides have been flattened, they may be passed between two other rollers having roughened surfaces for the purpose of crimping or roughening the surface of these sections, or the surfaces of 10 the first mentioned rolls may be roughened, in which case the flattening and roughening of the wire are brought about in a simple operation. In practice, I prefer to follow the latter practice. The roughened portion 15 is designated by the reference numeral 6 and is more clearly shown in Fig. 3 of the drawings.

In Fig. 4 of the drawings, I have shown for the purpose of illustration the ordinary 20 form of a resistance unit wherein the strip of wire is first bent at a point 7 near its middle to produce two substantially parallel sections. These parallel sections are then formed into a spiral 8 with the ends 9 and 25 10 arranged at the outside of the spiral. By reference to this figure, it will be noted that there is a tendency in a heating unit of this character for the loops 2 to contact with each other at the inside of a bend, such as at 30 the points 11 and 12. I have found that the flattening of the connecting portions 3 prevents contact of adjacent loops when the device is bent into the form of a spiral.

When it is desired to produce a heating 35 unit of greater capacity than can be obtained from a single resistance element, it is customary to arrange several of the heating elements shown in Fig. 4 upon each other and to separate them by strips of mica or 40 other insulating material. When the wire employed in constructing the elements is of substantially circular cross section, there is a tendency of the mica strips to become displaced and to permit contact of one element 45 with the element next above it. I have found that flattening the connecting sections of the wire employed in constructing such resistance elements, as at 4 and 5 in the drawings, greatly reduces this tendency of the 50 mica plates to become displaced. When these flattening portions are roughened, the tendency of the insulation to become displaced can be entirely overcome. When the heating unit is assembled, the mica plates 55 are placed on the top of a unit and a slight amount of pressure applied thereto. This pressure causes the roughened surface 6 to engage the surface of the mica and hold it firmly. Under such condition, the mica is

held in its proper position and relative 60 movement is entirely eliminated.

In the description and drawings, I have shown one advantageous embodiment of my invention, but it is apparent that the invention is not necessarily limited to the exact 65 form shown and described, and that changes may be made without departing from the spirit of the invention or the claims.

What I claim is:

1. An electrical resistance element comprising loops of wire of substantially circular cross section and connecting sections, the connecting sections being flattened to produce oppositely disposed elongated sections. 70

2. An electrical resistance element comprising loops of wire of substantially circular cross section and connecting sections, the connecting sections being flattened to produce oppositely disposed elongated sections, said elongated sections being rough- 75 80

3. An electrical resistance element comprising loops of wire, substantially circular in cross section, and connecting sections, said loops being arranged to produce a resistance element of any desired shape, said connecting sections being flattened on the 85 top and bottom. 90

4. An electrical resistance element comprising loops of wire, substantially circular in cross section, and connecting sections, said loops being arranged to produce a resistance element of any desired shape, said connecting sections being flattened on the top and bottom, and said sections being rough- 95 100

5. The method of constructing electrical resistance elements which comprises arranging a resistance wire in the form of loops and connecting sections, of substantially circular cross section, and flattening two sides of said connecting sections to produce oppositely disposed elongated sections. 100

6. The method of constructing electrical resistance elements which comprises arranging a resistance wire in the form of loops and connecting sections, of substantially circular cross section, flattening two sides of said connecting sections to produce oppositely disposed elongated sections, and 110 roughening said elongated sections. 105

In testimony whereof I affix my signature in presence of two witnesses.

ALBERT H. JOHNSON.
